(57) **CLAIM**

The ornamental design for a coat rack, as shown and described.

DESCRIPTION

FIG. 1 is a perspective view of the coat rack of the present invention, with a plurality of hangers shown in phantom for illustrative purposes;

FIG. 2 is a front view of a coat rack of the present invention; and,

FIG. 3 is a side view of the coat rack of the present invention leaning against a wall shown in phantom for illustrative purposes.

The lines shown in phantom are for illustrative purposes only and do not form part of the claimed invention.
